(57) **CLAIM**

The ornamental design for a bottle and cap combination, as shown and described.

DESCRIPTION

FIG. 1 is a perspective view of a bottle and cap combination showing the new design;

FIG. 2 is a front elevation thereof;

FIG. 3 is a rear elevation thereof;

FIG. 4 is a right side elevation;

FIG. 5 is a left side elevation;

FIG. 6 is a top view;

FIG. 7 is a bottom view;

FIG. 8 is a perspective view of a bottle with the cap removed;

FIG. 9 is a front elevation of a bottle with the cap removed therefrom; and,

FIG. 10 is a bottom view of the cap removed from the bottle. In the drawings, the broken lines show portions of the bottle that form no part of the claim.

1 Claim, 9 Drawing Sheets
